Primary Examiner — Shannon W Morgan*Assistant Examiner* — Terilyn Nicole Davis*(74) Attorney, Agent, or Firm* — Taylor J. Ross(57) **CLAIM**

The ornamental design for a rice dispenser, as shown and described.

DESCRIPTION

This application is related to co-pending U.S. application Ser. No. 17/381,765, filed Jul. 21, 2021, which is incorporated by reference herein.

FIG. 1 is a top, front and left side isometric view of a rice dispenser showing my new design;

FIG. 2 is a bottom, rear and left side isometric view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a cross-sectional view taken along line 9-9 of FIG. 3; and,

FIG. 10 is a cross-sectional view taken along line 10-10 of FIG. 3.

The internal portions of the rice dispenser shown in broken lines form no part of the claimed design.
